UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

BLINDSTITCH SEWING-MACHINE.

1,119,110.

Specification of Letters Patent.

Patented Dec. 1, 1914.

Application filed December 31, 1901. Serial No. 87,959.

To all whom it may concern...

Be it known that I, LANSING ONDERDONK, a citizen of the United States, residing at New York, in the county of New York, 5 State of New York, have invented certain new and useful Improvements in Blind-stitch Sewing-Machines, of which the following is a description, reference being had to the accompanying drawing, and to the 10 letters and figures of reference marked thereon.

My invention relates to an improvement in sewing machines, and particularly to a machine for blind stitching, the object being to provide a machine which shall be capable of use upon various kinds of work and on various styles of goods, and will be useful in sewing in hat sweats, sewing trousers bottoms, knit goods such as the tops 20 of stockings, and other work of this class where the market demands a blind stitch, and which shall also be capable of use for other kinds of work, as, for example, in uniting the edges of two abutting pieces of 25 fabric for making an overseam stitch for binding the edges of fabrics; and, in general, to produce a machine capable of great speed and durability and which, considering the uses to which it can be applied, shall 30 be comparatively simple in construction.

Certain features embodied in the machine which forms the subject matter of this application and of other co-pending applications upon segregable features, may be useful 35 on other machines than those of this particular type, and, therefore, it will be understood that the claims, in so far as they are applicable to other machines are not limited to this particular type.

40 The machine as a whole comprises various features, certain of which, as for example, the looper operating mechanism; the work support operating mechanism; the feed mechanism; and a supplemental top feed mechanism; form the subjects matter of other applications and are therein claimed *per se*, being herein claimed in combination with the features which make them especially applicable to this type, and in so 45 far as they form combinations and sub-combinations of the general invention.

The invention consists in the matters hereinafter described and referred to in the appended claims.

The invention is illustrated in the accompanying drawings, in which—

Figure 1 is a front elevation of a blind stitch sewing machine embodying my invention, this figure representing the preferred form; Fig. 1^a is a similar view representing certain modifications in the construction and operation, particularly, of the looper operating mechanism, the top feed and various other features being omitted therefrom; Fig. 2 is a rear elevation of the preferred form of my machine; Fig. 2^a is a rear view of the machine shown in Fig. 1^a; Fig. 2^b is a detail view showing the position of certain of the parts in Fig. 2 when the cylinder is lowered; Fig. 3 is an end view 70 of Fig. 1; Fig. 3^a is an end view of Fig. 1^a; Fig. 4 is a rear sectional end view of the machine shown in Fig. 1^a; Fig. 5 is a sectional side view, broken away through the center of the work support, both of these 75 figures illustrating principally the feed operating mechanism, it being understood, however, that these figures, so far as the work support operating mechanism shown in the lower part of said figures, is concerned, do not illustrate the preferred form; Fig. 6 is an end view similar to Fig. 4, but on a reduced scale, and with the upper part removed, showing the preferred form of my invention; Fig. 7 is a side view of Fig. 6 85 partly in section, showing the work supporting plate broken away, and the means for operating the same in detail; Fig. 8 is a front elevation of Fig. 1, with the goose-neck and overhanging arm removed and 90 showing the work support operating mechanism in section; Fig. 9 is a perspective view of the top feed mechanism detached; Fig. 10 is a vertical section taken through the forward end of Fig. 9; Fig. 10^a is a detail 95 perspective view of the feed dog and its immediate operating parts present in the machine shown in Fig. 1^a; Figs. 11 and 12 are end views of the work support, and top feed dogs in different positions; Fig. 13 represents a cross section of a seam sewed on my machine; Fig. 14 is a view similar to Fig. 9, showing the parts in a slightly different position; Fig. 15 represents a view in perspective of the preferred form of looper operating mechanism with its connections detached from the rest of the machine; Figs. 16 and 17 represent the looper and needle 100 105

relatively at their two extremes of movement; Figs. 18 and 19 are respectively front and rear views in detail of the modified form of looper operating mechanism present in 5 the machine shown in Fig. 1^a; Fig. 20 is a section showing the bearing for the looper supporting rod; Figs. 21, 22, and 23, represent in detail the presser foot and the looper and needle in different positions; Fig. 24 is 10 a sectional side detail view of the top feed tripping mechanism; Fig. 25 is a face view of the same; Fig. 26 is a detail view of the catch or stop to prevent the lowering of the work support when the needle is in the 15 goods; Figs. 27 and 28 are respectively side and end views; Figs. 29 and 30 are similar views, showing the needle and looper of the machine represented in Fig. 1^a in different positions; Figs. 31 to 36 represent in detail 20 the manner of forming the stitch with the machine shown in Fig. 1^a; Figs. 37, 38, and 39 are respectively front, rear, and sectional views of my special form of looper; Fig. 40 is a detail view of one of the presser feet; Fig. 41 is a detail view showing modifications of the presser foot bars, and the yoke connecting the same, upon which the spring bears to hold them down; Fig. 42 is 25 a front perspective view of the machine shown in Fig. 1, illustrating the presser bars and presser feet; Fig. 42^a is an enlarged plan view of the two presser feet; Fig. 43 is a front, side elevation illustrating a modified form of mechanism for operating the looper; and Fig. 44 is a detail view 30 of the fulcrum rod for the looper operating pitman.

In these drawings, A is the standard of a blind stitch sewing machine; B, the overhanging arm or goose-neck; and C, the work supporting plate, herein shown as a cylindrical casing inclosing the feeding mechanism and provided with a throat plate D, having openings for the passage of the feed 40 dogs, and provided with a V-shaped central rim or projection E, over which the goods are crimped. The needle F is herein shown as curved and reciprocates back and forth across the line of feed through the goods 45 crimped over the throat plate, taking a bite therein. The shank of this needle is secured in the lower end of a swinging lever G, which is pivoted to a stud H secured to the machine frame. The upper end of this 50 needle lever, as shown at I, is pivoted by a pivot pin K between the forks L on the head M secured to the pitman rod N. This pitman rod at its opposite end is connected to a strap O, which embraces the eccentric P on 55 the transverse driving shaft Q. As the driving shaft revolves, therefore, the needle reciprocates in the arc of a circle back and forth across the line of the feed. To prevent deflection of the needle in its movement 60 65 in case very thick or tough goods are to be

sewed, I provide upon opposite sides of the line of feed, needle guides, comprising arms a, which are secured at their upper ends to a lug b on the machine head, and at their lower ends have tapering openings c into 70 which the needle point passes and is guided in its movement.

The preferred form of looper operating mechanism is shown in Figs. 1, 2, and 15, and may be briefly described as follows: 75 To the rear side of the belt wheel R is attached the crank pin S, upon which is pivoted one end of the pitman rod 2, which at its opposite end embraces a ball stud 4 upon the crank 5 fixed to the rock shaft 6, journaled in the bearing barrel 7 on the head of the machine. Upon the opposite side of this bearing barrel and upon the rock shaft is fixed another crank 9, to which is pivotally secured a forked pin or bolt 10. 80 Between the forks of this pin or bolt 10 is pivotally secured the upper end of the looper supporting rod 11, which may be in one piece, or which, as herein shown, comprises the upper part 12 pivoted between the forks 85 and the lower part 13, screwed into a socket in the upper part. The shank of the looper 14, is secured in a collar or clamp 15 on the lower end of the rod 13. This rod 13, through the action of the cranks 5 and 9 90 is raised and lowered to impart to the looper a rise and fall, to enable it to pass from one side the line of the seam to the other over the apex or ridge on the throat plate, and to enable it to escape obstructions such as 95 seams or extra thicknesses of goods; but to impart this sidewise movement from one side the line of the seam to the other, it is necessary to freely pivot or fulcrum the 100 looper supporting rod, in order that as it rises and falls and the cranks pass from one side the center to the other, the tilting movement may be imparted; and to this end, I have provided the arm 16, enlarged at 105 its outer end and formed with a recess through which the rod 13 passes, this recess being formed to receive and hold a ball bearing 17. In the rise and fall, therefore, of said looper supporting rod it slides 110 through the ball 17, and at the same time oscillates said ball in its support, whereby the looper has the four motions above referred to. It is also necessary to impart to 115 said looper a forward and backward movement in the direction of its length, to enable it to take and leave the needle loop, and also to carry its own loop into position to be engaged by the needle, and to this end the arm 16 at its upper end is fixed upon an upright 120 rock shaft 18, journaled in bearing lugs 19 and 20, on the machine frame. The upper end of this rock shaft 18 has clamped about it one end of a rod or bar 21, which at its 125 opposite end has a ball and pitman connection 22, 23, with an eccentric 24, upon the 130

main shaft. As the shaft revolves, therefore, the vertical rock shaft is oscillated and the bearing through which the looper rod passes, and in which it is fulcrumed swings 5 from front to rear of the machine, thus imparting to the looper a backward and forward movement in the direction of its length.

Referring to Figs. 1^a, 2^a, 18, 19, and 20, a 10 slightly modified construction of looper operating mechanism is shown. In this arrangement, the pitman 23' extends at quite an inclination to the frame, and at its outer end is attached to a head *d*, which is pivoted 15 to the arm 21', which extends from the sleeve 18' arranged upon the inclined stud 18'. This sleeve has another extending arm 16', which carries upon its outer end a clamping head *e*, which incloses the ball 18'. The 20 looper supporting rod 13, passes through this in the manner above described. The vertical and sidewise movements to the looper are imparted to it through the oscillating crank shaft 6, having the cranks 5 and 9, 25 the upper end of the looper supporting rod or bar 13 having a ball and stud connection *f*, with the crank 9. The operation of the parts is substantially as described in connection with the mechanism shown in Fig. 15.

30 The looper shown in the various figures of the drawings is of special construction, and is shown in detail in Figs. 37, 38, and 39. This looper has a recess on its under side, as shown at 25, the rear shoulder of 35 this recess forming a projection 26, which, in the movement of the looper engages the thread and holds it in position, so that the needle will pass between the under side of the looper and the looper thread. In other 40 words, the looper carries on its under side, a spreading device for its own loop, which spreading device acts as shown in Figs. 31 to 36, of the drawings, Fig. 31 showing the looper just entering the needle loop; Fig. 45 32 the looper about one-half way over to the other side of the seam, with the looper thread under the looper. Fig. 33 shows the looper in position preparatory to moving back before the needle engages the looper 50 thread, the said looper thread having been engaged by the projection upon the under side of said looper. In Fig. 34, the looper is shown as having moved back from the position shown in Fig. 33, with the point of the 55 needle just passing under the looper, preparatory to engaging the looper thread. Fig. 35 illustrates a cross section of the looper, the point being cut away, but the looper thread shown in full lines; in this 60 drawing, the point of the needle having engaged the looper thread and the looper thread being brought into position by the projection on the under side of the looper. Fig. 36 represents the looper passing back 65 over the goods, back of the path of the

needle to position preparatory to again entering the needle loop.

I will now describe the means for operating the cylindrical work support, of which two different forms are shown, and will 70 refer particularly to the preferred forms which are illustrated in Figs. 1, 6, 7, and 8. The cylindrical work support is hinged at its rear end to the standard A, by means of the rock shaft D². E' is a hand lever secured to the shaft E², passing through the base or standard of the machine, said hand lever swinging close to the front side thereof. Fixed to the shaft E², and adjacent the inside face of the standard of the machine is 80 an arm or lever piece 27, to which is pivotally secured by a shoulder screw, the link 29, which link at its opposite end is pivotally secured by the screw 30 to the arm or lever 31, loosely sleeved on the shaft 32 85 journaled in the machine standard. The arm or lever 31 is provided with an upwardly projecting lug or arm 33, which engages the lower end of the latch 34, which is loosely sleeved on said shaft 32, and is 90 provided with an extension 35, which the lug or arm 33 is adapted to engage when the shaft is rocked in one direction.

Upon the shaft 32 within the standard, 95 near the opposite side thereof from the arm 31, is a similar arm or lever 36 fixed to said shaft, and having an upwardly projecting arm or lug 37, adapted to engage the extension 38 on the latch 34. Freely secured to the shaft 32 on the outside of the standard is a square headed collar piece 39, on the square head of which is securely fastened the lifting lever 40, intended to be connected with a foot treadle or knee lever under the machine table by any suitable 100 means.

D³ is an extension of the cylinder or work support which passes down inside the machine standard. 42 is a bracket, secured inside the standard, and provided with a barrel 43, in which is located a plunger 44, free to slide endwise in its bearings. The inner end of the plunger 44 is normally forced against the part D³ by a spiral spring 45, the pressure of which is regulated by a 110 thumb screw 46. The action of the spring and plunger against the extension D³ keeps the work support in place against the work or presser foot, or against the screw A⁵, which regulates the position of the work support and consequently the amount of bite of the needle into the goods. When the hand lever E' is up, the action of the spring 45 and plunger 44 causes the work support to rest against the stop A⁵. Now by moving the lever E' down, the shaft E² will rock, and the lever 31, through the medium of the connecting link 29, and the extension 33, will engage the part 34 and swing back the lower end of D³, thus lowering the work 120 125 130

support to allow the insertion of the goods. When the toggles 27 and 29 become straightened then the lever arm 31 has been moved down as far as possible, and the work support is held in depressed position, the arm E' and its connections overbalancing the pressure of the spring 45. To hold the cylinder down more securely, however, I swing said lever E' down so as to cause the connections to pass by the center line of the toggles when straightened out, when said lever will be stopped by the lower lug e² coming in contact with the stop pin e'. By moving the lever E' up when its connections pass to the other side of the center, the spring 45 will force the cylinder to place, the lever being prevented from going too far by the upper lug e, coming in contact with the stop pin e'.

It will be seen that the manipulation of the hand lever E' and its parts in action against the work support is independent of the foot lever 40 and its associated parts; 31 and 34 are mounted freely on the shaft 32, while 36 and 39 are fixed thereto. By moving the lever 40 down, the shaft 32 with the lever 36 is made to turn, thus engaging the latch 34, and controlling the work support. It is intended to have the foot lever connections through 39, 40, etc., control the cylinder or work support only when the treadle is pushed down by the operator's foot, in order that the operator may cause the cylinder to swing down by the pressure of her foot and by releasing the same, the cylinder will go up to place by the action of the spring plunger, without necessitating the removal by the operator of her hands from the work, but when it is desired to hold the cylinder down away from the needle and presser foot, she can lock it in such position by using the hand lever E'.

The spring 47 is arranged to press against the link 29 when in locked position, so that by putting pressure upon the foot treadle and relieving the strain caused by the action of the spring 45, this spring 47 will act against the link 29 sufficiently to move it to the other side of the center when the spring 34 will cause the parts to move up to place; thus the lever can be unlocked by the foot leaving the operator's hands free. This construction permits of a slight automatic yield to the work plate under the action of a seam or increased thickness of goods, substantially as set forth in my prior Patent No. 721,081, granted Feb. 17, 1903.

Certain special arrangements, whereby the lowering of the work support is prevented when the needle is in the goods, and also certain arrangements whereby the top feed mechanism is thrown out of action automatically when the work support is lowered to permit of the insertion of the work, will be hereinafter referred to.

In Fig. 5 particularly, is shown a modified construction of mechanism for operating the work support, in which the barrel in which the plunger slides is pivoted, and is operated by a hand lever E', the spring pressed plunger normally keeping the work support up against the screw A⁵. The form above particularly described, however, is preferable, and forms the subject matter of my prior Patent No. 745,736, granted Dec. 1, 1903.

The feeding mechanism of the machine includes two coöperating feeding arrangements, one a lower feed mechanism inclosed within the cylindrical bed plate or casing, and carrying feed dogs which have up and down and reciprocating movements, and the other, a top feed mechanism. These feeding mechanisms may be used separately, but for certain purposes, the coöperation of the two, makes the machine much more efficient, and I will now proceed to describe the same, and first the lower feeding mechanisms.

Between the two bearing points of the main or driving shaft on the standard, and in front of the gooseneck or overhanging arm, are secured two eccentrics g, h, which operate two upright connecting rods i, k, the lower end of connecting rod i, being secured by ball and socket connection to the horizontal lever l. This lever l is fixed at its outer end to a shaft m, journaled in bearings in lugs on the front of the machine standard, and is provided at its forward end with a curved slotted cross head into which is fitted the head of a bolt n. On the bolt n, is a ball sleeve o held firmly in place by the nut and washer p, q.

Around the ball sleeve o is clamped one end of the connecting rod s, the opposite end of which has a ball and socket connection with the crank sleeve t, fixed to one end of the feed dog actuating shaft u, which extends through the cylindrical bed plate, having suitable bearing lugs therein, and at its forward end is secured to a head 48, having a rectangular slot 49 in its lower end through which passes a pivot pin 50, having a squared head 51, to the outer end of which pivot pin is attached the lower end of the feed dog carrying bar 52, having the feed dogs 53, which feed dog carrying bar 52 is pivotally attached to one end of the link 54, fixed to the outer end of the shaft u', by which the vertical movements are imparted to the feed dog; the bar 52 sliding up and down as the link 54 oscillates.

The eccentric connection i, through the lever l, shaft m with slotted cross head, bolt n, sleeve o, connecting rod s, and sleeve t, form a universally jointed arrangement of parts through which a conveniently adjustable oscillating movement is imparted to the feed shaft u during a revolution of the eccentric g, secured to the driving shaft. It is this oscillation of shaft u, which deter-

mines the length of stitch, the variation of oscillation of said shaft being effected by the adjustment of connecting rod *s*, through parts *n*, *o*, *q*, to and from the center of the transverse shaft *m*.

The lower end of connecting rod *k* is secured by a ball and socket connection to the bell crank lever *x*. Said bell crank lever *x*, is secured on the transverse shaft *m'*, journaled in bearings in lugs extending from the rear side of the machine standard, the lugs being represented at *y z*. To the lower end of *x* is secured by ball and socket connection the connecting rod *s'*, this ball and socket connection being adjustable in the slot in bell crank lever *x*. The other end of the connecting rod *s'* has a ball and socket connection with a crank sleeve *w'*, which is firmly secured to the feed shaft *u'*, through which connection, oscillatory motion is imparted to the shaft *u'* from the driving shaft.

The purpose of the adjustable connection between the bell crank lever *x*, and the connecting rod *s'* is for the purpose of increasing or diminishing at will, the up and down movement of the feed dog, which is particularly desirable in a machine of this kind, to meet the variations in thickness and nature of the material to be sewn. Also by the ball and socket connection of parts, it will be seen that the cylindrical work support or bed plate may be dropped or raised more or less, without affecting the action of the shafts *u*, *u'*, and, therefore, the feed dog and the connecting parts will not bind.

When the machine is to be used for certain classes of work, particularly in blind stitching trousers-bottoms, it is desirable and in fact almost necessary, to use a top feed mechanism co-operating with the lower feed. As herein shown, this top feed mechanism is connected to, and operated by, the lower feed mechanism, although it will be understood that such is not absolutely necessary, as other means may be devised for operating the said top feed mechanism.

Referring now to Figs. 1, 2, 8, 11, 12, and 14, 55, and 56, represent two feed dogs having teeth in their lower forward edges, projecting one, 55, into the space between the two presser feet 57, 58, and the other, 56, extending alongside the presser foot 57. These feed dogs 55 and 56 are fixedly sleeved at the front of the machine to a shaft 59 extending longitudinally of the work support, and journaled in the upper ends of arms 60, 60, fixed at their lower ends to the rock shaft 61, journaled in bearings in a lug 62, secured to the work support. This rock shaft is provided with an upwardly and outwardly extending arm 63, in which near its upper end is fitted a bolt 64, upon which is pivoted one end of a link 65, which at its opposite end is pivoted on a bolt 66, secured to the upper

end of the arm 67, which latter is, at its lower end, clamped upon the shaft *u*. It will be seen, therefore, that as the shaft *u* oscillates the shaft 61 rocks, and swings the arms 60 bodily, thus moving the feed dogs 70 55 and 56 bodily back and forth. Near its inner end, the shaft 59 has loosely mounted upon it a downwardly projecting arm 68, which, at its lower end is provided with a stud 69, upon which is pivoted one end of a curved link 70, which, at its lower end is pivoted on the stud 71, secured in the lower end of the lever or crank 72, loosely sleeved on the shaft *u'*. This lever or crank 72 is normally pinned to the crank 73, fixed at its upper end to the shaft *u'*. This pinning together of the two cranks is accomplished by means of a spring catch 74, pivoted to the crank 73, and having a latch engaging the slot 75 in the crank 72. 85

When the cranks 72 and 73 are pinned together, they move as one and the oscillations of the shaft *u'* transmit an oscillatory movement to the arm 68. A leaf spring 76 is secured in the split end of the shaft 59, and rests at its lower end between projections 77 on the arm 68. When the arm 68 is swung through its connection to the shaft *u'*, the projections will engage first one side and then the other of the leaf spring 76, and through the leaf spring 76 impart an oscillatory movement to the shaft 59, thus swinging the forward ends of the feed dogs 55 and 56 up and down. This will cause the feed dogs to be yieldingly pressed against the fabric and allow unequal thicknesses of fabric to pass beneath the feed dogs, without in any way retarding or interfering with the feed.

Means are provided for automatically releasing the top feed mechanism when the work plate is lowered for the insertion or removal of the work, and to this end, the spring catch 74 has its lower end projecting downwardly into position to be engaged by a projection 77^a on the machine standard, whereby when the work support is lowered, the catch will be tripped, and release the crank 72 from engagement with the crank 73, holding the catch in disengaged position until the work support returns to elevated position, and the shaft *u'* begins to oscillate, when the cranks are again united. This stop arm moves with the feed, so that its end passes alternately into and out of position, just back of the extension D^a of the work support, and is so timed that it moves back of the same when the needle is in the goods, and the feed is not taking place, so that any attempt to lower the work support at such time, will cause the extension D^a to bear against the stop 78, and thus hold said work support from downward movement.

I have only briefly referred to the looper operating mechanism shown in Figs. 1^a, 9^a, 180

3^a, 18, 19, and 20, because the construction illustrated in the other figures of the drawings is the one which I prefer to use, but, so far as the machine is concerned, either arrangement is practical, and the operation of forming the stitches substantially the same in both styles of mechanism, and is illustrated in Figs. 31 to 36, inclusive, which have been heretofore referred to. The relations of the needle and looper of the modified construction shown in said Figs. 1^a, 2^a, 3^a, 18, 19; and 20, is more clearly illustrated in Figs. 27 to 30, inclusive, but no special stress is herein laid on said particular looper operating mechanism, because it is only broadly included in the claims of this case. In Fig. 43, however, still another modification of looper operating mechanism is disclosed, in which the driving shaft Q is provided with a beveled gear 85, meshing with a similar gear 86 supported on an inclined axis, and having a hub 87 carrying a crank provided with a crank pin 88, to which is attached one end of the pitman rod 23'; to the opposite downwardly extending end of which is secured the looper 14. This pitman rod is pivoted between the arms 89 of a block 90 having a turning bearing through the medium of the short shaft 91, supported in a lug 92 on the machine frame. It will be seen, therefore, that through the crank and the universal fulcrum the looper has all the necessary movements to enable it to pass into and out of the needle loop, raise and lower from one side to the other of the line of feed, and deliver its thread properly for engagement with the needle.

In Figs. 21 to 23, inclusive, another way of forming the stitch from that illustrated in the remaining figures of the drawings, is shown. In these figures, the presser foot 58 is shown as provided with a loop-retaining wire 100, secured to the presser foot by the screw 101, although said loop retaining wire 45 might be secured to the head of the machine. In Fig. 21, the looper thread is shown as caught upon the retainer. Fig. 22 shows the looper below the needle with the thread around the retainer and spread thereby, and Fig. 23 illustrates the looper drawing back with the needle above the looper thread about the time at which the loop is drawn off the retainer. This construction is to be used when the looper in its movement, passes 50 below the path of the needle, instead of being above it all the time, as shown in Figs. 31 to 36; in which latter event the notch and shoulder on the under side of the looper perform the function of the retainer upon the presser foot shown in Figs. 21 to 23. This arrangement is not herein specifically claimed, although it may form the subject matter of another application.

In Figs. 41, 42 and 42^a, is represented the 65 presser foot mechanism, comprising, as above

mentioned, the two feet 57 and 58, adapted to coöperate with the feed dogs 53, projecting up through the throat plate upon each side the apex or ridge E, over which the goods are crimped. The presser feet are 70 secured respectively to the presser bars 93 and 94, which move vertically in the head of the machine. Near their upper ends below the upper lug 102, the presser bars have secured to them collars 103 from which project rearwardly pins 104 upon which rests a plate or yoke 96, a presser spring 95 bearing upon said plate or yoke to keep the presser feet normally depressed. The presser feet 75 57 and 58 are made of the shape shown for the purpose of giving a proper clearance to the looper, and also to allow the thread to draw up when being set in the stitch. The part 58' projecting transversely from the inner part of the presser foot 58 is for the 80 purpose of pushing down ravelings from the cut edge of the seam, where one is to be sewed on the machine, and also to act as a retainer for the looper thread as the looper is about to enter the needle loop. The projection 58' furthermore acts to guide the looper thread and insure the engagement of the spreading device on the under side of the looper with said looper thread as it is drawn over the projection. It will be 85 noted that the looper moves forward on one side of the line of seam, and then across the line of seam to position its loop for the entrance of the needle, and it is then withdrawn from the needle loop, 90 moving again across the line of seam to enter the next needle loop. The projection 58' is on the opposite side of the line of seam from that entered by the needle. As the looper moves forward into the needle 95 loop, the thread running to the previous locking of the threads will be drawn directly across the finger or projection 58'. When the looper moves across the line of seam to position its loop for the entrance of the 100 needle, the looper thread will be carried along the projection 58' and slip from the end thereof. The pin 106 projecting from the presser foot 57, is for the purpose of engaging the top feed, when the work support is moved back to operative position, so 105 as to press the top feed down upon the work.

By referring to Fig. 11, it will be noticed that the throat plate is provided with an off-set O, and this is for the purpose of allowing seams to get out of the way after having passed the needle, thus allowing the work supporting arm to bring the thinner portion of the work immediately up to the desired point for the needle to properly 115 enter the same, on the first stitch after the seam shall have passed beyond the path of the needle. It is in effect the same as though the heel of the presser foot ended within the length of a stitch back of the 120 125 130

needle's path. Thus this off-set of the throat plate comes within the length of an ordinary stitch back of the path of the needle. The presser foot not conveniently admitting of the form desired in a compact construction, this substantial equivalent thereof, is provided on the throat plate so that at the point where the work passes abruptly from thick to thin, the thin portion will be brought within the path of the needle so the needle will enter it, and not materially vary the depth of the needle's bite into the goods, or skip stitches in going abruptly from thick to thin work, as is necessary in passing from the top of a seam down to a considerably less thickness. Without this, offset in the throat plate or its equivalent, the needle would fail to enter the thin body of the goods until the seam had fed free of the presser foot as the thickness of the seam would hold the work support, and consequently the goods down out of the way or path of the needle. The operation of this part in connection with sewing is shown in Fig. 13.

Various minor modifications and changes may be made in the construction of the various parts of this machine without departing from the spirit of my invention.

Having thus described my invention, what I claim as new, and desire to secure by Letters Patent, is:—

1. In a sewing machine having a suitable work support, stitch-forming mechanism, an under feeding mechanism, a top feed mechanism, means for raising and lowering the work support for the insertion and removal of the work, and means for throwing the top feed mechanism into and out of operation as the work support is raised and lowered.

2. In a sewing machine in combination with a suitable work support, means for moving the same, feeding mechanism contained therein, a supplemental top feed mechanism, means for throwing the top feed mechanism into and out of operation as the work support is moved, a needle reciprocating above the work support across the line of the feed, a vertically arranged looper-supporting bar arranged above the work support, a looper thereon, a universal support for said looper-supporting bar, and means for imparting to said looper-supporting bar a bodily vertical movement, a swinging sidewise movement and a bodily forward movement in the direction of the length of the looper.

3. In a sewing machine, in combination with a suitable work support, means for moving the same, a feeding mechanism supported thereby, a needle reciprocating back and forth across the line of the feed above the work support, means brought into action by the work support in its movement for

throwing the feed into or out of operation, and a looper coöperating with said needle also arranged above the work support.

4. In a sewing machine, in combination with an overhanging frame, a suitable work support pivoted to the standard and extending parallel with the overhanging frame, feeding mechanism contained therein, a top feed mechanism supported thereby, a needle reciprocating back and forth across the line of feed, a looper coöperating therewith above the work support, and means for raising and lowering the work support.

5. In a sewing machine, in combination with a suitable work support, feeding mechanism contained therein, a top feed mechanism supported thereby, a needle reciprocating back and forth across the line of feed, a looper coöperating therewith above the work support, and means for raising and lowering the work support and for throwing the top feed mechanism into and out of operation as the work support is raised and lowered.

6. In a sewing machine, in combination with a suitable work support, feeding mechanism contained therein, a top feed mechanism supported thereby, a needle reciprocating back and forth across the line of feed, a looper coöperating therewith above the work support, means for raising and lowering the work support, said top feeding mechanism being connected with and operated by the main feed mechanism, and means for releasing the two when said work support is lowered to release the top feed mechanism.

7. In a sewing machine having suitable stitch-forming mechanism and having a work support with means for raising and lowering it, a feeding mechanism with means operable by the movement of the work support for throwing the same into and out of operation as the work support is moved.

8. In a sewing machine having suitable stitch-forming mechanism and having a work support with means for raising and lowering it, a feeding mechanism carried by said work support, and means operable by the movement of the work support for automatically throwing it into and out of operation as the work support is moved.

9. In a sewing machine having suitable stitch-forming mechanism and having a work support with means for operating it, a feeding mechanism supported on the work support and adapted to engage the work, and means operable by the movement of the work support for throwing the feed mechanism out of operation as the work support is moved.

10. In a sewing machine having suitable stitch-forming mechanism and having a work support, with means for raising and

- lowering it, a top feed mechanism with means for throwing it into and out of operation as the work support is moved.
11. In a sewing machine having suitable 5 stitch-forming mechanism and a work support, and means for raising and lowering the same, a feeding mechanism, and a spring catch controlling the feeding mechanism, with means for tripping the same when the work support is lowered.
12. In a sewing machine having suitable 10 stitch-forming mechanism and a work support, and means for raising and lowering the same, a top feeding mechanism, a spring catch controlling the same, and means for tripping the latter when the work support is lowered.
13. In a sewing machine having suitable 15 stitch-forming mechanism and a work support, and means for raising and lowering the same, a top feeding mechanism, a spring catch controlling the same, and a projection on the machine frame for tripping the spring catch when the work support is lowered.
14. In a sewing machine having a suitable 20 work support, means thereon for crimping the work, a complementary presser foot device, stitch-forming mechanism including a needle reciprocating back and forth across the line of the seam, a looper coöperating therewith, and a separate guide for the needle located upon each side the line of seam above the presser foot device.
15. In a sewing machine having a suitable 25 work support, means thereon for crimping the work, a complementary presser foot device, stitch-forming mechanism including a needle reciprocating back and forth across the line of the seam, a looper coöperating therewith, and arms above the presser foot device provided with a tapering guiding opening in each, adjacent the line of the seam through which the needle passes.
16. In a sewing machine having stitch-forming mechanism and a suitable work support, provided with a ridge or projection over which the goods are crimped, and having a complementary presser foot device.
- needle guides arranged upon each side of said ridge or projection above the presser foot device.
17. In a sewing machine, stitch-forming mechanism and a suitable work support provided with a ridge or projection over which the goods are crimped, of a presser device comprising two parts and having an opening to receive said ridge or projection, and a needle guide above each part of the presser foot.
18. In a sewing machine having a suitable work support provided with a ridge or projection over which the goods are crimped, of a presser foot device composed of two parts and having an opening to receive said ridge or projection, and a needle guide above each part of the presser foot, the presser foot having also a guiding slot for the passage of the needle.
19. In a sewing machine having suitable 70 stitch-forming mechanism and a suitable work support, provided with a ridge or projection over which the goods are crimped, of two presser feet, one upon each side of said ridge or projection, and top feed dogs, 75 one between the presser foot, one alongside the inner presser foot, and means for operating said feed dogs.
20. In a sewing machine having suitable 80 stitch-forming mechanism and a work support, and overhanging frame relatively movable with respect to each other, of means for preventing such relative movement while the needle is in the goods.
21. In a sewing machine having a work 85 support and overhanging frame, said parts being relatively movable to allow of the insertion and removal of the work, and stitch-forming mechanism including a needle reciprocating back and forth across 90 the line of feed, of means for preventing such relative movement of the work support and overhanging frame while the needle is in the goods.
22. In a sewing machine having a relatively movable work support, and overhanging frame, and including a needle reciprocating back and forth across the line of the feed, of a movable stop operable by a moving part of the machine mechanism for preventing such relative movement of the work support and overhanging frame while the needle is in the goods.
23. In a sewing machine having a feeding mechanism, and stitch-forming mechanism including a needle reciprocating back and forth across the line of feed, and a relatively moving work support and overhanging frame, a device operated by the feeding mechanism for preventing such relative 105 movement of the work support and overhanging frame while the needle is in the goods.
24. In a sewing machine having stitch-forming mechanism and having a work support, with means for raising and lowering it; means independent of said means for raising and lowering it for preventing the lowering thereof except at certain periods in the stitch-forming operation.
25. In a sewing machine having stitch-forming mechanism and having a work support, means for raising and lowering it, and means operated by the feed mechanism of the machine for preventing the lowering of 125 said work support except at certain periods in the stitch-forming operation.
26. In a sewing machine having suitable

- stitch-forming mechanism, and a work support with means for raising and lowering it to allow of the insertion and removal of the work, a stop, with means for moving it into the path of the work support to prevent lowering thereof except at certain periods during the operation of the stitch-forming mechanism.
27. In a sewing machine, the combination with suitable stitch-forming mechanism, a swinging work support, a feeding mechanism, and a swinging arm with connections between it and the feeding mechanism for moving said arm into and out of engagement with the work support to prevent or permit of movement of said work support.
28. In a sewing machine having a work support hinged to the machine standard and adapted to be raised and lowered, an arm secured to a rocking shaft on the machine frame and movable into the path of the work support to prevent lowering thereof, and operative connections between the said rocking shaft and the driving shaft, said connections including also the connections which actuate the feeding mechanism, whereby said movable arm is timed in unison with the feed mechanism.
29. In a sewing machine having a suitable work support, with means for raising and lowering it, to allow of the removal or insertion of the work, means for crimping the work laid on said support, a needle with means for reciprocating it back and forth through the crimped portion of the goods, a looper coöperating therewith to form stitches, a vertically arranged bar supporting the same with means for moving it bodily up and down, for swinging it sidewise, and for bodily moving said bar back and forth in the direction of the length of the looper, and a guide for the needle arranged upon each side the crimped portion of fabric.
30. In a sewing machine having a suitable work support, with means for raising and lowering it, to allow of the removal or insertion of the work, means for crimping the work laid on said support, a needle with means for reciprocating it back and forth through the crimped portion of the goods, a looper coöperating therewith to form stitches, a vertically arranged bar supporting the same with means for moving it bodily up and down, for swinging it sidewise, and for bodily moving it back and forth in the direction of the length of the looper, and a guide for the needle arranged upon each side the crimped portion of fabric.
31. In a sewing machine having a suitable work support, with means for raising and lowering it, to allow of the removal or insertion of the work, means for crimping the work laid on said support; a needle with means for reciprocating it back and forth through the crimped portion of the goods, a looper coöperating therewith to form stitches, a vertically arranged bar supporting the same with means for moving it bodily up and down, for swinging it sidewise, and for bodily moving it back and forth in the direction of the length of the looper, arms attached to the machine frame and extending down upon opposite sides of the crimped portion of fabric, each provided with a tapering opening to receive and guide the needle in its forward movement.
32. In a sewing machine having a suitable work support, with means for raising and lowering it, to allow of the removal or insertion of the work, means for crimping the work laid on said support, a needle with means for reciprocating it back and forth through the crimped portion of the goods, a looper coöperating therewith to form stitches, a bar supporting the same with means for moving said bar bodily up and down, for swinging it sidewise, and for bodily moving it back and forth in the direction of the length of the looper, and means for preventing the lowering of the work support while the needle is in the goods.
33. In a sewing machine having a suitable work support, with means for raising and lowering it, to allow of the removal or insertion of the work, means for crimping the work laid on said support, a needle with means for reciprocating it back and forth through the crimped portion of the goods, a looper coöperating therewith to form stitches, a bar supporting the same with means for moving it bodily up and down, for swinging it sidewise, and for bodily moving said bar back and forth in the direction of the length of the looper, and two presser feet arranged upon opposite sides of the line of feed, and a guide for the needle arranged upon each side the crimped portion of fabric.
34. In a sewing machine having a suitable work support, with means for raising and lowering it to allow of the removal or insertion of the work, means for crimping the work laid on said support, a needle with means for reciprocating it back and forth through the crimped portion of the goods, and two presser feet, one upon each side the line of feed, one of which is provided with a guiding slot for the passage of the needle, and a guide for the needle upon each side said guiding slot.
35. In a sewing machine having a suitable work support, with means for raising and lowering it to allow of the removal or insertion of the work, means for crimping the work laid on said support, a needle with means for reciprocating it back and forth through the crimped portion of the goods, two independent presser feet, one upon each side the line of feed, and supplemental top feed dogs, one of which extends into the space between the presser feet, and the other is outside one of the presser feet.
36. In a blind stitch sewing machine, in combination with a stitch-forming mechanism and fabric-directing members including a work support, a throat plate carried by the work support, a crimping rib carried by the throat plate, and a presser foot coöperating with said crimping rib, one of said fabric-directing members having an offset located back of the path of the needle in the direction of

feed, whereby in sewing goods in the passage from thick to thin material, the needle will get the proper bite into the goods.

36. In a blind stitch sewing machine, in combination with a stitch-forming mechanism and work support, a throat plate carried by the work support, and a presser foot coöperating therewith, said throat plate being provided with an offset downward back 10 of the path of the needle, whereby in sewing goods in the passage from thick to thin material, the needle will get the proper bite into the goods.

37. A sewing machine including in combination, a work support, means for crimping the work laid over the work support, stitch-forming mechanism including a needle, means for reciprocating the same back and forth through the crimped portion 15 of the goods, a thread-carrying looper and spreading device coöperating with said needle, a presser foot coöperating with the crimping means, a projecting member carried by the presser foot and extending laterally therefrom, said projecting member being so disposed as to act as a guide for the 20

looper thread to insure the engaging of the spreading device with said looper thread as it is drawn over said projecting member.

38. A sewing machine having in combination, an overhanging arm, a work support, a ridge or projection carried by the work support over which the goods are crimped, stitch-forming mechanism carried by said overhanging arm, a presser foot composed 35 of two independently yielding parts adapted to engage the work on opposite sides of the ridge, and having an opening between the same, whereby the needle may pass through the crimped portion of the goods 40 lying on said ridge and between the parts of the presser foot, and a feeding mechanism having feeding portions located on opposite sides of said ridge and coöperating respectively with the parts of the presser 45 foot.

In testimony whereof I affix my signature, in presence of two witnesses.

LANSING ONDERDONK.
